S. ZYSKOWSKI,
CURTAIN HOLDER,
APPLICATION FILED APR. 11, 1919.

Patented Feb. 24, 1920.

2 SHEETS—SHEET 2.

FIG. 11.

Inventor
Stanislaw Zyskowski
By Adam E. Dratz
Attorney

UNITED STATES PATENT OFFICE.

STANISLAW ZYSKOWSKI, OF CHESTER, PENNSYLVANIA.

CURTAIN-HOLDER.

1,331,738.

Specification of Letters Patent.

Patented Feb. 24, 1920.

Application filed April 11, 1919. Serial No. 289,387.

To all whom it may concern:

Be it known that I, STANISLAW ZYSKOWSKI, a citizen of Poland, residing at Chester, county of Delaware, and State of Pennsylvania, have invented certain new and useful Improvements in Curtain-Holders, of which the following is a specification.

This invention relates to improvements in curtain holders and has as its special object 10 the provision of means whereby draperies, shades and curtains of any description may be attached so as to partially or wholly obscure the window over which they are engaged.

15 A further object is to provide a holder of the device which may be elongated or contracted to suit different widths of window openings, and

20 A still further object is to provide means whereby the fixtures may be attached rigidly to the window frame without the use of screws or like securing means.

25 These and other like objects are attained by the novel construction and combination of parts hereinafter described and shown in the accompanying drawings, forming a material part of this disclosure, and in which:—

30 Figure 1 is a fragmentary plan view showing a fixture made in accordance with the invention.

Fig. 2 is a side elevational view thereof.

Fig. 3 is an end elevational view of the same.

35 Fig. 4 is a fragmentary top plan view showing a modified form of construction.

Fig. 5 is a side elevational view thereof.

Fig. 6 is another fragmentary top plan view showing a further modification in construction.

40 Fig. 7 is a side elevational view of the same.

Fig. 8 is a plan view of a blank before bending into the support bracket.

45 Fig. 9 is a side elevational view showing a modified form of the engaging means, and

Fig. 10 is a view of the connecting elements used in connection therewith.

50 Fig. 11 is a perspective view showing the bracket in position on the window.

The device is comprised of a pair of oppositely disposed bracket elements 10, each having overhanging front portions 11, provided with downwardly extending edges 12,

while at the lower edge of the main vertical portion are upturned longitudinal edges 14, forming in effect a runway adapted to receive the slide 15, having extending portion 16, adapted to engage with the rear wall 10 60 of the brackets, and the front of the longitudinally downward edge 12.

Formed with the sliding plate 15 is an ear 18, containing an opening 19 receptive of the shade roller ends. 65

In the horizontal upper element 16 of the sliding plate, are formed a plurality of circular perforations 20, the same being alinemental with the single opening 21, formed in the top plate 11, and engageable with the 70 alinemental openings are the points or spurs 23, of a detent 24, pivoted in a clip bracket 25, formed by pressing upward the material of the upper plate, thus when a longer or shorter shade pole is used, the ears 18 are 75 moved relatively to the end of the slide by raising the detent 24 and, when the plate is adjusted, dropping it through the opening 21 and into any of the perforations 20 formed in the plate, thereby locking the 80 slide in the bracket in an obvious manner.

Attached to the back of the bracket is a rigid flat extension 28, containing a vertical passage 29, receptive of the stem 30 of obliquely disposed plate supports 31, bent 85 laterally at the top 32 and also at the ends 33, the end elements being slotted, receptive of a flat bar 35, provided with a twisted hook-like extension 36, adapted to receive a curtain drapery pole, which with the bar 30 90 may be adjusted lengthwise with reference to the bracket 31 so as to extend the curtain at a greater or lesser distance from the window, the opposite end of the sliding bar 35 being bent to form a stop 37 preventing its 95 complete withdrawal.

Formed with the extension 28 at the upper and lower edges on each side, are a plurality of sharp spur elements 38 adapted to be driven into the woodwork in the manner 100 of a nail, thereby holding the fixtures permanently engaged with the window frame, and without the use of screws, nails or the like.

In the modification shown in Figs. 4 and 5, the same general construction is used except that in the cover or top plate 11, of the bracket, in place of a round opening 21 an elongated slot 40 is made, the same being adapted to receive the bent end of a bar 41, 110

pivoted at 42 in a double sided handle 43, pivoted on a pin 44, set in the bracket 45, formed with the top plate 11, the construction being such that as the lever handle 43 is moved outwardly upon its pivotal point, the engaging bent end of the bar 41 acts to move the plate 11 outwardly, causing a sliding effect between the plate and bracket, so that an adjustment of the same may readily be obtained.

In the modification shown in Figs. 6 and 7, the openings 20 are engaged by a finger 48, formed with a lever arm 49, pivoted at 50 to a loop handle bar 51 in turn pivoted 15 on a pin 52, set in a bracket 53, so that an adjustment between the plate and bracket may be obtained in addition to a spring element 54, pressing against a pivoted block 55, holds the lever handle 51 against accidental displacement.

In Figs. 8 to 10 inclusive is shown another modified form of the structure, the same consisting of a base plate 60, having arcuately formed lateral portions 61, provided 25 with teeth in the manner of segments 62 and containing perforations 63, which upon the sides being folded, receive a pin on which is pivoted a lever 66 engaged with a pawl 64, pivoted at 65, on the arm 66, which 30 extends downwardly between the raised segment 61, and has pivoted by a pin 67, an arm 68 terminating in a prong or finger 69 adapted to engage in the openings 70, of a bar 71, carrying an ear 72, in the manner before mentioned, it being understood 35

that a guide bracket is provided for the bar 71.

The detent or pawl 64 is raised from the teeth of the segments by a rod 74, provided by an operative knob 75, on the end extending upwardly from the arm 66, the operation and construction in other respects being as previously described.

Having thus described my invention what I claim as new and desire to secure by Letters Patent, is:—

In a curtain holder, the combination with a bracket adapted to be attached to a window frame, a runway connected to said brackets, a slide arranged in said runway and provided with a plurality of perforations, a top plate provided with a single opening adapted to be brought into alignment with said perforations, said perforations and opening adapted to be engaged by a detent pivotally secured to said top plate, a rigid, flat extension provided with a vertical passage and a plurality of spurs on each of said brackets, obliquely disposed plate supports entering with their stems said 60 passages and having looped upper ends, flat bars passing through said looped ends, a twisted hook-like extension on said bar for the reception of a drapery pole and a stop element on said bar preventing its complete 65 withdrawal from said loops, substantially as described.

In testimony whereof I have affixed my signature.

STANISLAW ZYSKOWSKI.
